FLOOR JACK

Marvin Wiggins, Fort Myers, Fla.

Application November 23, 1948, Serial No. 61,579

7 Claims. (Cl. 254—16)

1

This invention relates to devices for facilitating laying tongue and groove flooring and in particular includes a small tool that is clamped on a joist or framing member and which is provided with a hand lever by which considerable pressure may be placed against a piece of flooring to force the tongue into the groove and which also holds the flooring tight until it is nailed.

The purpose of this invention is to provide a flooring jack for tightening up tongue and groove flooring so that the joint may be completely closed.

It is always difficult to lay tongue and groove flooring with tight joints as it is desired to have the tongue fit tightly in the groove and for this reason the grooves do not slide freely over the tongues. Most carpenters hammer the tongue to force grooves over the tongue of the next piece of flooring and this upsets the tongue so that it is difficult to force the next piece of flooring over. With this thought in mind this invention contemplates a jack that may readily be moved from one joist to another and which is adapted to be quickly clamped to the joist and readily actuated by a hand lever to force or jam the groove of one piece of flooring over the tongue of another.

The object of this invention is, therefore, to provide a unique flooring jack that is adapted to be quickly clamped on a joist and which includes a forcing element that not only forces the flooring together but holds the flooring in position until it is nailed.

Another object of the invention is to provide a hand actuated jack for forcing pieces of tongue and groove flooring together that may readily be released after use.

Another object of the invention is to provide a floor jack for forcing tongue and groove flooring together that may readily be folded so that it may be carried in the average tool box.

A further object of the invention is to provide an improved floor jack for holding tongue and groove flooring while nailing which is of a simple and economical construction.

With these and other objects and advantages in view, the invention consists in the features of construction, combination and arrangement of parts as will be hereinafter more fully described, illustrated in the accompanying drawings, which show the preferred embodiment of the invention as pointed out in the claims hereunto appended.

In the drawings:

Figure 1 is a plan view of the floor jack illus-

2

trating the device on a floor joist with the forcing bar in engagement with a piece of flooring and with the hand lever broken away;

Figure 2 is a view showing a side elevation of the floor jack with the parts in the position as illustrated in Figure 1;

Figure 3 is a vertical longitudinal section through the floor jack taken on line 3—3 of Figure 1 and with the parts in the same relative positions;

Figure 4 is a view showing an end elevation of the floor jack taken on line 4—4 of Figure 3; and

Figure 5 is a cross section through the jack taken on line 5—5 of Figure 2.

Referring now to the drawings where-in like reference characters denote corresponding parts the floor pack of this invention is formed with a base 10 having a forcing bar 11 slidably mounted on the forward end, clamping sides 12 and 13 pivotally mounted on the base by pins 14 and 15 respectively, a cam 16 actuated by handle 17, and a hand lever 18 removably mounted in a socket 19 by a thumb screw 20.

The base 10 is formed of a flat rectangular shaped member and the bar 11 is carried by pins 21 and 22 which extend into sockets 23 and 24 in the forward end, respectively. The bar 11 is provided with a groove 25 that is adapted to fit over a tongue 26 of a piece of flooring 27. The bar 11 is actuated by the hand lever 18 through the socket 19 which is pivotally mounted by a pin 28 in lugs 29 and 30 that are mounted on the base 10 by screws 31. The socket 19 is connected to the bar 11 by a brace 32 that has a bifurcated upper end, the sections of which are held on a pin 33, the ends of which extend from the sides of the socket 19. The opposite end of the brace is attached to the bar 11 by a hinge clip 34 with screws 35. After the hand lever 18 has been drawn forward to force the flooring into place, it is held in this position by a latching bar or latch 36, which is pivotally mounted on the socket by a pin 37, the opposite end of the bar being provided with a projection 38 that drops into teeth 39 in the upper surface of the base 10, as shown in Figure 3.

The jack is clamped in operative position by the side plates 12 and 13 through the cam 16, the sloping sides of which engage lugs 40 and 41 on the inner surface of the plates 12 and 13, respectively; and as the handle 17 of the cam is forced downwardly the lugs 40 and 41 are forced outwardly which action forces the points 42 and 43 into the sides of a joist 44. The sides 12 and 13 are resiliently held with the lugs 40 and 41 against

the cam by a spring 45 the ends of which are attached to the upper ends of the sides. The cam 16 is pivotally mounted in the sides 12 and 13 by a pin 46 and the handle 17 is attached to the bar 36 by a chain 47.

With the parts arranged in this manner the jack may be placed on a floor joist, as indicated by the numeral 44, and the handle 17 pressed downwardly to force the points or teeth 42 and 43 into engagement with the sides of the joist. The groove of the forcing bar 11 may then be placed over the tongue of a piece of flooring and the hand lever 18 drawn forward to force the flooring into position. As the hand lever moves forward the projection 38 drops into a tooth 39 thereby locking the parts in position until the flooring is nailed. After the flooring is secured in place, the jack is released by raising the hand lever 17 which in turn draws the bar 36 upward by the chain 47 thereby releasing the hand lever and clamping elements.

The hand lever 18 may be readily removed from the socket 19 for convenient packing in a tool box or the like by removing the thumb screw 20.

It will be understood that modifications may be made in the design and arrangement of the parts without departing from the spirit of the invention.

What is claimed is:

1. A tool for tightening tongue and groove flooring comprising a base, cam actuated gripping jaws pivotally mounted on the base for temporarily clamping the tool to a floor joist, a hub having beveled end surfaces journaled in the jaws and having an extended handle, said beveled surfaces of the hub coacting with corresponding inner surfaces of the jaws whereby upon rotation of the hub the jaws are actuated to gripping relation with the floor joist, a forcing bar carried by the forward end of the tool and slidably mounted on the said base, a hand lever pivotally mounted on the tool, a brace connecting the hand lever to the forcing bar, said base having spaced teeth in the upper surface, and a latch carried by the hand lever and positioned to engage the teeth in the upper surface of the base of the tool to lock the forcing bar in operative position until the flooring is nailed.

2. A tool for tightening tongue and groove flooring, comprising a base having a plurality of teeth in the upper surface and spaced from one end thereof, cam actuated gripping jaws pivotally mounted on the sides of the base and extended upwardly and downwardly from the base, a hub having cam surfaces on the ends and an extended handle pivotally mounted in the jaws whereby upon rotation thereof the upper ends of the jaws are spread apart and the lower ends thereof are forced together for clamping the base to a floor joist, a forcing bar carried by the forward end of the base and slidably mounted thereon, a hand lever pivotally mounted on the base, a brace connecting the hand lever to the forcing bar, and a latch carried by the hand lever and having a projection thereon positioned to engage the teeth in the upper surface of the base to lock the forcing bar in operative position while the flooring is nailed.

3. A tool for tightening tongue and grooved flooring, comprising a base having teeth in the upper surface and spaced from one end thereof, side plates pivotally mounted on the base and extending upwardly and downwardly therefrom, said side plates having lugs with sloping surfaces on the inner sides thereof, a cam with sloping ends

5 pivotally mounted in the side plates with the ends positioned to engage the lugs thereof, means resiliently urging the side plates against the ends of the cam, said cam having a handle extending therefrom by which it may be rotated to force the lower ends of the side plates into clamping engagement with a floor joist upon which the tool is positioned, a forcing bar carried by the forward end of the base and slidably mounted therein, a hand lever pivotally mounted on the base, a brace connecting the hand lever to the forcing bar, and a latch carried by the hand lever and having a projection positioned to engage the teeth in the upper surface of base to lock the forcing bar in operative position while flooring is nailed.

4. A tool for tightening tongue and groove flooring, comprising a base having teeth in the upper surface and spaced from one end thereof, side plates pivotally mounted on the base and extending upwardly and downwardly therefrom, said side plates having lugs with sloping surfaces on the inner sides thereof, a cam with sloping ends pivotally mounted in the side plates with the ends positioned to engage the lugs thereof, means resiliently urging the side plates against the ends of the cam, said cam having a handle extending therefrom by which it may be rotated to force the lower ends of the side plates into clamping engagement with a floor joist upon which the tool is positioned, a forcing bar carried by the forward end of the base and slidably mounted therein, a hand lever pivotally mounted on the base, a brace connecting the hand lever to the forcing bar, a latch comprising a bar having a projection on the end thereof pivotally mounted on the hand lever and extended whereby the projection engages the teeth in the upper surface of the base and a flexible element connecting the handle of the cam to the said bar pivotally mounted on the hand lever and having the projections thereon for releasing the latch as the cam is released.

5. A tool for tightening tongue and groove flooring, comprising a base, side plates extending upwardly and downwardly from the base and pivotally mounted thereon, said side plates having lugs on the inner surfaces thereof, a cam pivotally mounted in the side plates having sloping surfaces adapted to engage the lugs on the inner surfaces of the side plates, said cam having a handle extending therefrom for actuating the cam to spread the upper ends of the side plates for forcing the lower ends of the side plates into clamping engagement with a floor joist on which the jack is positioned, a spring connecting the upper ends of the side plates holding the lugs thereof in engagement with the ends of the cam, a hand lever pivotally mounted on the base, a forcing bar positioned at the forward end of the base, means connecting the hand lever to the forcing bar, and a latch for locking the hand lever in operative position.

6. A tool for tightening tongue and groove flooring comprising a base, side plates extending upwardly and downwardly from the base and pivotally mounted thereon, said side plates having lugs on the inner surfaces thereof, a cam pivotally mounted in the side plates having sloping surfaces adapted to engage the lugs on the inner surfaces of the side plates, said cam having a handle extending therefrom for actuating the cam to spread the upper ends of the side plates thereby forcing the lower ends of the side plates 70 into clamping engagement with a floor joist on

which the tool is positioned, a spring connecting the upper ends of the side plates holding the lugs thereof in engagement with the ends of the cam, a hand lever pivotally mounted on the base, a forcing bar positioned at the forward end of the base, means connecting the hand lever to the forcing bar, a latch for locking the hand lever in operative position and means releasing the latch as the cam is released.

7. A tool for tightening tongue and groove flooring comprising a base having teeth in the upper surface and spaced from one end thereof, side plates pivotally mounted on the base, a cam pivotally mounted between the side plates and having a handle extending therefrom, said cam adapted to spread the upper ends of the side plates, thereby forcing lower ends thereof into engagement with a joist upon which the jack is positioned, means urging the upper ends of the side plates against the cam, a hand lever pivotally mounted on the base, a flooring forcing element

connected to the hand lever and adapted to be operated thereby, a latching element carried by the hand lever and having a projection to engage the teeth of the base for locking the hand lever in the position of holding the flooring until the flooring is secured in position, and means connecting the latching element to the cam whereby the latching element is released as the cam is released.
